UNITED STATES PATENT OFFICE.

JAMES M. SCHOFIELD, OF MERCED, CALIFORNIA.

SAFETY-TIP FOR PENCILS.

SPECIFICATION forming part of Letters Patent No. 390,038, dated September 25, 1888.

Application filed May 23, 1888. Serial No. 274,892. (No model.)

To all whom it may concern:

Be it known that I, JAMES M. SCHOFIELD, of Merced, Merced county, California, have invented an Improvement in Safety-Tips for 5 Pencils; and I hereby declare the following to be a full, clear, and exact description of the same.

My invention relates to the class of pencil-tips; and my invention consists in a rubber tip piece or band adapted to be applied to the pencil and formed or provided with prongs of the same material.

The object of my invention is to prevent the pencil from dropping from the pocket, as 15 it is liable to do when a person is in a leaning position.

Referring to the accompanying drawings for a more complete explanation of my invention, Figure 1 shows the application of my 20 tip in the form of a round rubber eraser in the end of a metal cylinder applied to the pencil permanently or removably, as desired. Fig. 2 shows my tip in the form of a flat piece of rubber. Fig. 3 shows it in the form of an 25 independent band.

The tip A is of rubber, and is formed or provided with a prong or prongs, B, of the same material. This tip may be applied to the pencil C directly or indirectly, or in any 30 of the customary ways of securing erasers thereto. Thus in Fig. 1 it is shown connected by a metal cylinder, D, which may be either

of the kind permanently attached to the pencil or adapted to be removed from one end and put on the other in order to protect the 35 point.

In Fig. 2 the rubber tip is a flat one, in which case I deem a single prong, or at most two, sufficient.

In Fig. 3 the tip is an independent rubber 40 band, which is fitted over the pencil and may or may not serve as an eraser.

In all cases the prongs serve to hold the pencil in the pocket by catching in the material of the pocket, but yet, on account of their 45 yielding character, they do not appreciably resist a positive effort to withdraw the pencil when necessary; nor, on account of being made of rubber, do they injure the clothing in any manner; nor do they affect the 50 function of the tip as an eraser.

Having thus described my invention, what I claim as new, and desire to secure by Letters Patent, is—

A safety-tip for pencils, consisting of a piece 55 of rubber fitted to the pencil and provided or formed with a prong or prongs of rubber, substantially as described.

In witness whereof I have hereunto set my hand.

JAMES M. SCHOFIELD.
